Primary Examiner — Messina L Smith*Assistant Examiner* — Aram Kwon(74) *Attorney, Agent, or Firm* — Nitin Kaushik(57) **CLAIM**

The ornamental design for a keyboard switch, as shown and described.

DESCRIPTION

FIG. 1 is a front perspective view of a keyboard switch, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of an encircled portion of the keyboard switch labeled 9 in FIG. 1.

The evenly-dashed broken lines in the drawings illustrate portions of the keyboard switch that form no part of the claimed design.

The dash-dot-dash broken lines encircling portions of the keyboard switch illustrated in enlargements form no part of the claimed design.
